DESIGN FOR A WEIGHING SCALE

George D. Barok, Columbus, Ohio

Application March 2, 1945, Serial No. 118,237

Term of patent 14 years

(Cl. D52—10)

To all whom it may concern:

Be it known that I, George D. Barok, a citizen of the United States, residing at Columbus, in the county of Franklin and State of Ohio, have invented a new, original, and ornamental Design for a Weighing Scale, of which the following is a specification, reference being had to the accompanying drawing, forming a part thereof.

Fig. 1 is a perspective view of a weighing scale showing my new design;

Fig. 2 is a top plan view thereof.

I claim:

The ornamental design for a weighing scale, as shown.

GEORGE D. BAROK.
